UNITED STATES PATENT OFFICE

ALFRED SCHMIEDER, OF MASPETH, NEW YORK

SCREW CLAMP

Application filed January 18, 1930. Serial No. 421,658.

My invention relates to improvements in means for clamping parts in position to facilitate the securement or working thereof, such as in the art of woodworking, and the same has for its object to provide a simple, efficient and reliable device which is readily manipulated and secured in position to exert a clamping action along a plurality of lines of direction, or at a plurality of points.

10 Another object of the invention is to provide a device of the character specified in which certain of the clamping components thereof are capable of being relatively moved to exert conjointly a third clamping action along a line of direction extending transversely relative to the lines of direction of said clamping components.

Another object of the invention is to provide a device of the character specified in which an attachment may be readily connected to a pair of ordinary clamps for causing positive movement thereof towards each other to exert a clamping action along a line of direction extending transversely relative to the lines of direction of the individual clamps.

Another object of the invention is to provide a device of the character specified in which certain of the clamping components are retained against slipping relative to the work when moved towards each other.

Other objects will in part be obvious and in part be pointed out hereinafter.

In the accompanying drawings:

25 Figure 1 is a perspective of one of the clamps of the device constructed according to and embodying my said invention.

Fig. 2 is a plan of the device with parts in section;

40 Fig. 3 is an elevation thereof with parts broken away;

Fig. 4 is a section thereof on the line 4—4 of Fig. 2;

Fig. 5 is a plan showing a modification;

45 Fig. 6 is an elevation thereof with parts broken away; and

Fig. 7 is a section thereof on the line 7—7 of Fig. 5.

50 Referring to the drawings the clamping means includes a pair of clamps 10 and 12,

each comprising a standard 14 having a lower arm 16 secured thereon and upper arm 18 slidable thereon. The outer end of lower arm 16 is provided with a universally swiveled abutment or member 20 adapted to engage a piece or member to be clamped and the outer end of the upper arm 18 is provided with a screw 22 threaded therethrough and having a universally swiveled abutment 24 cooperating with the abutment 20. The two clamps 60 55 10 and 12 are substantially alike in construction.

The clamps 10 and 12 are connected together by means 26 for moving the clamps toward each other to conjointly exert a clamping action along a transverse line. The connecting means 26 includes a pair of members 28 and 30 preferably provided with slots 32 and 34 receiving the standards 14. The members 28 and 30 are adjustably secured to the 70 65 standards by the set screws 36.

The members 28 and 30 are provided with lateral ears or lugs 38 at the inner sides thereof towards the front and similar lugs or ears 40 at the rear thereof. The members 28 and 30 are pivotally connected through ears 40 to the ends of a one piece bridging member 42, having an interiorly threaded central portion 44 forming a nut meshing with the clamping screw or actuating member 46. The inner end 48 of the screw 46 is rotatably retained or swiveled in the member 50 having ears 52. Links 54 pivoted at the ends thereof to the ears 38 and 52 form a toggle-like arrangement for controlling the movement of the clamps 10 and 12 about their pivots on member 42.

At Figs. 5, 6 and 7 I have illustrated a modified arrangement 26^a for controlling the transverse clamping. In the latter form the standard engaging members 28 and 30 are substantially identical with those illustrated at Figs. 1 to 4, the same including the ears or lugs 38 and 40 and being secured by the set screws 36.

The members 28 and 30 are bridged by a one piece member 56 pivoted at its ends to the ears 38 and having an enlarged central portion 58 provided with an opening receiving the inner end of the clamping screw 46^a for 100 95 100

rotatably retaining the same. An interiorly threaded nut member 60 meshes with the screw 46^a. Links 62 are pivotally connected at the ends thereof to the ears 40 and ears 64 on the member 60 forming a toggle-like arrangement in this case, located at the rear of the clamps 10 and 12 for swinging the latter about their pivots on member 56.

The surfaces of the abutments 20 and 24 are roughened or ribbed as indicated at 66 to provide a surface capable of biting into the work to prevent slipping thereon when the clamps 10 and 12 are moved towards each other.

15 The portions 66 may be of any suitable configuration or design, such as the reticulated design shown at Figs. 1 to 4 or the circular design shown at 66^a, Fig. 5.

In operation, the actuating means 26 or 26^a are readily secured to the clamping components 10 and 12 by engaging the slotted portions 32 and 34 with the standards 14 and, after being adjusted for height, are secured by set screws 36. The clamping components 25 10 and 12 are then engaged with the pieces of the work by adjustment of the screws 22. By rotating the screw 46 or 46^a considerable force is developed and the clamping components 10 and 12 move through an ample range towards and away from each other, while resisting slipping relative to the work, to exert a third clamping action along a transverse line and cause the pieces of the work to be firmly pressed into engagement with each other at the contiguous edges thereof.

30 In my invention the clamping components 10 and 12 therefore form conjointly a third clamping component, thereby rendering the device more universal and flexible and enlarging the usefulness thereof.

40 The clamps 10 and 12 in the present invention are connected together by parallel transverse connections, one of which serves as the pivoted connection for the clamps and the other of which as the actuating means. The clamping screw 46, 46^a, has the axis thereof at a right angle to the parallel connections and is connected centrally to both thereof.

50 My device may be readily manipulated and secured in position without the actuating means being in the way of the work, and provides three different clampings. The working or securing of the pieces is thereby greatly facilitated and the device may be employed in connection with types of work for which the individual clamps 10 or 12 are inadequate, thereby providing a device having an enlarged range of usefulness, and particularly in connection with the fabrication of veneered articles, the gluing of joints of various forms, and working upon curved surfaces.

55 Having thus described my invention what

I claim and desire to secure by Letters Patent is:

1. A device of the character described comprising slotted members for attachment on the standards of a pair of clamps and having lateral and rear attaching lugs, an intermediate member pivotally connected at the ends thereof to one set of corresponding lugs of said first named members, another intermediate member, and links pivotally connected to said last named member and the remaining set of lugs, and a screw meshing with one of said intermediate members and having the end thereof rotatably connected to the other.

70 2. A device of the character described comprising a pair of clamps each including a standard and relatively adjustable clamping members thereon, and a connection therebetween including standard engaging portions having lugs thereon, a spacing member pivotally connecting the lugs of one set, an actuating connection between the lugs of the other set, and an actuating member coacting with said spacing member and said actuating connection.

75 3. A device of the character described comprising a pair of clamps each including a standard and relatively adjustable clamping members thereon, and an attachment including portions slidably engaging said standards for adjustment longitudinally thereof, and having lateral lugs and lugs at the rear thereof, a spacing member pivotally connecting the lugs of one set, an actuating connection between the lugs of the other set, and a screw coacting with said spacing member and said connection.

80 4. A device of the character described comprising a pair of clamps including standards and clamping members slidably engaging said standards, and an actuating attachment including portions slidably engaging said standards for adjustment relative to said clamping members, a spacing member pivotally connected to said portions, a toggle therebetween, and an actuating screw between said spacing member and said toggle.

85 5. A device of the character described comprising a pair of clamps including standards, arms slidably adjustable longitudinally of the standards relative to each other, and relatively adjustable clamping members at the outer ends of the arms, slotted members slidably engaging said standards for adjustment longitudinally thereof between said arms and having forward and rear lugs thereon, an intermediate member pivotally connected at the ends thereof to the lugs of one set, another intermediate member, links pivotally connected thereto and to the lugs of the remaining set, and a screw coacting with said intermediate members.

90 6. A device of the character described comprising an attachment for swinging clamps

towards each other to exert a third clamping action including members adapted to engage the standards of the clamps for sliding adjustment longitudinally thereof, spacing means pivotally connecting said members, an actuating connection between said members in spaced relation to said spacing means, and a screw coacting with said spacing means and said actuating connection.

10 In testimony whereof, I have signed my name hereto.

ALFRED SCHMIEDER.
